UNITED STATES PATENT OFFICE

141,068

DESIGN FOR A FLUORESCENT LIGHTING FIXTURE

René G. Maurette, Beverly, Mass., assignor to
Sylvania Electric Products Inc., Salem, Mass.,
a corporation of Massachusetts

Application May 8, 1943, Serial No. 110,162

Term of patent 14 years

(Cl. D48—23)

To all whom it may concern:

Be it known that I, René G. Maurette, a citizen of the United States, residing at Beverly, in the county of Essex and State of Massachusetts, have invented a new, original, and ornamental Design for a Fluorescent Lighting Fixture, of which the following is a specification, reference being had to the accompanying drawing forming part thereof.

Figure 1 is a side elevational view of a fluorescent lighting fixture showing my new design;

Figure 2 is a front elevational view thereof; and

Figure 3 is a perspective view thereof.

I claim:

The ornamental design for a fluorescent lighting fixture, as shown.

RENÉ G. MAURETTE.
